UNITED STATES PATENT OFFICE.

EDWARD KUTIN, OF HARRAH, OKLAHOMA.

CLOTHES-PIN.

1,274,286.

Specification of Letters Patent. Patented July 30, 1918.

Application filed March 5, 1918. Serial No. 220,575.

To all whom it may concern:

Be it known that I, EDWARD KUTIN, a citizen of the United States, residing at Harrah, in the county of Oklahoma, State of Oklahoma, have invented certain new and useful Improvements in Clothes-Pins; and I do hereby declare the following to be a full, clear, and exact description of the invention, such as will enable others skilled in the art to which it appertains to make and use the same.

The invention relates to a clothes pin, and more particularly to the class of metal or spring wire clothes pins.

15 The primary object of the invention is the provision of a clothes pin of this character, wherein the construction thereof avoids the possibility of the breaking or splitting of the same, thereby increasing the life of the pin and will assure the firm holding of articles upon a clothes line, the pin being entirely devoid of wood so that climatic conditions will not affect the same.

Another object of the invention is the provision of a clothes pin of this character, wherein the construction thereof is novel in form so that the same can be readily opened and closed for the application of the pin to a line or its removal therefrom.

30 A further object of the invention is the provision of a clothes pin of this character, wherein the jaws thereof are made from single length wires and said jaws are assembled to assure compactness and durability in the use of the pin.

35 A still further object of the invention is the provision of a clothes pin of this character, which is extremely simple in construction, strong, thoroughly reliable and efficient in its purpose, and inexpensive to manufacture.

With these and other objects in view, the invention consists in the features of construction, combination and arrangement of parts as will be hereinafter fully described, illustrated in the accompanying drawing and pointed out in the claim hereunto appended.

In the accompanying drawing:—

50 Figure 1 is a side elevation of a clothes pin constructed in accordance with the invention.

Fig. 2 is a top plan view thereof.

Fig. 3 is a vertical transverse sectional view on the line 3—3 of Fig. 2.

Fig. 4 is a perspective view of a modified form of clothes pin.

Similar reference characters indicate corresponding parts throughout the several views in the drawing.

Referring to the drawing in detail, the clothes pin comprises a pair of pivotally connected spring held jaws A and B respectively, each formed from a single length of rigid wire bent on itself to provide a substantially U-shaped frame 5 of the desired width and the legs or limbs 6 of this frame being bent to form coils 7 which register with each other for receiving a sleeve 8 which swingingly connects both frames together.

The ends of the wire forming each frame 5 are extended in divergent relation rearwardly of the coils 7 and have mounted thereon a finger piece or handle 9 in the form of a metal plate which is provided with a transverse depression constituting a bulge 10 at its inner face and through this bulge which is provided with suitable openings 11 are passed the ends of the wire of the frame 5 so that in this manner the finger pieces or handles 9 are carried by and fastened to the frames.

Located within the sleeve 8 is a coiled spring 12 which has the end portions thereof bent at right angles thereto to form arms 13 which are provided with inturned ends 14 engaged in eyes 15 bent outwardly from the limbs 6 of the frames 5 and this spring 12 normally holds the jaws A and B closed and under tension.

Passed through the coils of the spring 12 is a pivot 16 which has fixed thereon end washers 17 against which play the outermost coil 7 on one of the frames 5 to prevent the spreading apart of the limbs 6 of both frames 5 and in this manner the jaws A and B are pivotally connected for opening and closing movement.

In Fig. 4 of the drawing there is shown a modification of the invention, wherein in lieu of the finger pieces or handles 9 and the washers 17 there are substituted the handles 18 which are formed with the pivot ears 19 through which is passed the pivot pin 20 and engaged with these handles 18 are the ends of the wires forming the frames 21 constituting the jaws of the clothes pin. The frames 21 are constructed similarly to the frames 5 hereinbefore described,

From the foregoing it is thought that the construction and manner of operation of the invention will be clearly understood and therefore a more extended explanation has been omitted.

However it is to be understood that changes, variations and modifications may be made in the invention such as come properly within the scope of the appended claim, 10 without departing from the spirit of said invention or sacrificing any of its advantages.

What is claimed is:—

A clothes pin comprising a pair of substantially U-shaped frames forming jaws, each frame having a pair of coils bent there-

from, a sleeve engaged in the coils transversely of the frames, a coiled spring within the sleeve, eyes formed on the frames, arms formed at the ends of the spring and 20 engaged in the eyes, a pivot passed through the coils of the spring, and handles active upon the frames for permitting the opening of the jaws against the resistance of the spring.

25

In testimony whereof, I affix my signature, in the presence of two witnesses.

EDWARD KUTIN.
